UNITED STATES PATENT OFFICE

2,342,850

APPARATUS FOR ELECTROPLATING METAL STRIP

John F. Ferm, Midland, Pa., assignor to Crucible Steel Company of America, New York, N. Y., a corporation of New Jersey

Application January 30, 1941, Serial No. 376,658

8 Claims. (Cl. 271—2.3)

This invention pertains to improvements in electroplating apparatus, and more especially such as is adapted to the plating of continuous metal strip, by the use of pinch rolls interpolated between successive plating zones, and which are so coordinated with pinch rolls located beyond the plating zones that non-uniform and excessive tension on the strip, and slippage of the strip with respect to the feed rolls, while passing through the plating zones, are eliminated.

As regards the feeding of the strip through the plating bath, one practice has heretofore been to pull the strip over "idler" rolls disposed throughout the bath, by means of power driven "pinch" or "bridle" rolls positioned on the exit side of the bath. This is unsatisfactory owing to the progressively increasing tension, productive of breakage, exerted on the strip as it passes through the bath. In long plating lines this tension on the strip may increase in the ratio of as much as 7 or 8 to 1 from the input to the output end. Alternatively it has been proposed to apply a positive drive to feed rolls distributed along the bath, which, however, is productive of slippage of the rolls against the strip, due to slight irregularities in roll driving speeds, tension in the strip, etc., whereby the surface of the strip is scratched and marred.

In accordance with this invention, it is proposed to eliminate this objectionable arrangement by employing in conjunction with the power driven pinch rolls on the exit side of the bath, other power driven pinch rolls positioned at intervals along the bath, these latter rolls, however, being individually connected to a source of driving power through over-drive, slip clutches, preferably so adjusted that the tension exerted on the strip by the exit pinch rolls very slightly under-drives the positively driven parts which drive the clutch driven pinch rolls, the ideal adjustment being that at which the strip drives these rolls at exactly the same speed at which they are driven through their associated slip clutches. With this arrangement the strip merely "floats" on the clutch driven rolls, with no slippage and subject to uniformly low tension.

Referring now to the drawings:

Fig. 1 is a plan view, in more or less schematic form, of a plating bath in accordance with the invention for plating continuous strip, the bath consisting, in this instance, of seven plating sections.

Fig. 2 is an enlarged plan view, corresponding to portions of Fig. 1, but showing one of the plating sections considerably more in detail.

Fig. 3 is a longitudinal section taken at 3—3 of Fig. 2.

Fig. 4 is an enlarged view in side elevation of one of the plating sections as viewed from below in Fig. 2.

Fig. 5 is a transverse section in elevation taken at 5—5 of Fig. 2, this view illustrating the relative arrangement of the contact roll assembly and the manner in which these rolls are driven through the overdrive, friction clutches above referred to.

Fig. 6 is a sectional detail, taken at 6—6 of Fig. 2, and illustrating the manner in which the plating racks are supported and connected to the electrical bus bars.

Fig. 7 is a view taken substantially at 7—7 of Fig. 5, partially schematic and partially in section, to illustrate the mode of adjusting the pressure between rolls of the contact roll assembly.

Fig. 8 is an enlarged plan view of one of the contact roll assemblies illustrating the manner in which the contact shoes are connected to the bus bars.

Fig. 9 is a perspective view of one of the contact shoes in accordance with the invention.

Fig. 10 is an enlarged sectional view, taken at 10—10 of Fig. 2, and illustrating the construction of the overdrive, frictional clutch construction for driving the contact rolls.

Fig. 11 is a section at 11—11 of Fig. 10.

Referring to the several figures of the drawings in which like elements are similarly designated, the apparatus comprises an elongated sheet metal plating tank 1, mounted on supports 2, and filled to about the level 3 with plating solution. The metal strip 4 to be plated, is fed repeatedly into and out of the bath by means of the contact roll assemblies 5 positioned above the bath, and the pairs of idler rolls 6, 7 immersed therein, the strip passing into the bath between the rubber or like covered lower roll 8 and the upper metal roll 9 of a contact roll assembly 5, thence under an idler roll 6 beneath the surface of the plating solution, and thence between a series of upper and lower plating racks 10, 11, on which are placed bars, such as 12, 13, of the material to be plated, thence under an idler roll 7, and out of the bath between the rolls 8, 9 of the next succeeding contact roll assembly, whereby the bath is divided into a number of plating sections for progressively plating strip. The entire plating bath comprises, as shown in Fig. 1, seven such plating sections 14, the contact roll assemblies 5, for all of which, are driven by a common motor 15 through a

shaft 16, extending the length of the bath, and in a manner explained more in detail hereinafter.

Referring more particularly to Figs. 3, 5 and 7, each of the contact roll assemblies 5 comprises, as stated, a lower roll 8 covered with an electrical insulating material, such as rubber, rubber composition, etc., and an upper roll 9, which is entirely of metal. Rolls 8, 9 are journaled into bearings, such as 17, 18, Fig. 7, respectively, which are so supported as to be vertically adjustable with respect to each other, for varying as desired the pressures between the rolls. To this end, bearings 17 are bolted, as shown, to frame members 19, which in turn are bolted to, and carried by, the supports 2 for the plating tank 1. The bearings 18 are in turn bolted, as shown, to open frame members 20, which in turn are vertically adjustable in guides 21, secured to frame 19.

Each of the frames 20 is centrally supported at the top, by a bolt 22, which passes at its lower end through an apertured plate 23, forming part of the frame 20, this bolt being provided with a flanged lower end for purposes of such support. At their upper ends, the bolts 22 pass through an apertured cross member 24, forming part of the frame 19, and are threaded thence through gear members 25 rotatable by worms 26, keyed to a shaft 27, whereby frame 20 may be raised and lowered by rotation of the shaft. For causing roll 9, when lowered sufficiently, to exert resilient pressure on roll 8, a washer 28 is pin-connected, as shown in Fig. 7, to each bolt 22, and between this washer and the associated plate 23 of frame 20, is interposed a helical spring 29, whereby sufficient downward adjustment of the bolts 22 causes a variable degree of resilient pressure to be exerted between rolls 8, 9. For manipulating the worm gears 25, 26, shaft 27 has keyed thereto a handwheel 30.

Considering now, with reference to Figs. 2, 4 and 5, the manner in which driving power is applied to rolls 8, 9, motor 15 drives a spindle 35 through a worm and gear drive indicated at 36, Fig. 2. Keyed to spindle 35 is sprocket 37, which drives through chain 38, a sprocket 39 keyed to shaft 16. At each of the contact roll assemblies 5, the shaft 16 has keyed thereto a bevelled gear 40 meshing with a cooperating gear 41 keyed to a spindle 42, journaled through bearings 43, carried by the frame supports 2. Also keyed to spindle 42, is a sprocket 44, which drives through chain 45, a sprocket 46, forming part of an overdrive, friction clutch 47 mounted on shaft 48 of roll 9, whereby roll 9 is driven from sprocket 44 through the friction clutch 47.

The construction of the overdrive, friction clutch is shown more particularly in Figs. 10, 11, referring to which, the sprocket 46 is bolted, as shown to a bushing 47a formed of insulating material such as a suitable laminated phenolic product, disposed between and shaped to interengage in keyed relationship, a pair of peripherally flanged metal collars 48a, 49, which are spaced apart as indicated at 50, and which are journaled on a sleeve member 51, having a flanged inner end 52, against which the inner collar 48a frictionally engages. The sleeve member 51 has threaded onto its outer end, a bushing 53, forming part of a handwheel 54. Interposed between the outer collar 49 and the bushing 53, are ring members 55, 55a, containing peripherally spaced recesses, for reception of a series of helical springs 56 positioned between these ring members. The collar 49 frictionally en-

gages the ring member 55, under the pressure of springs 56. The ring members 55 and 55a may be slidably keyed as indicated to sleeve 51. Sleeve 51 is journaled on an inner sleeve 57, this inner sleeve having a flanged inner end 58 abutting the inner end of sleeve 51, and having secured to its outer end a retaining washer 59 engaging a recess in sleeve 51, as shown, for securing the two sleeves 51, 57 together. The shaft 48, for roll 9, is keyed as indicated in sleeve 57, and sleeve 57 has keyed in its outer end a member 60, containing a diametrical slot, in which are slidably mounted a pair of driving pawls 61, 62, spaced resiliently apart by an interposed helical spring 63. The pawls 61, 62 engage the teeth of a ratchet ring 64, which is keyed to sleeve 51 as shown. The pawls 61, 62 are held in place by a cover plate 64a, bolted to the outer end of sleeve 51.

In the operation of this clutch, the motor 15 applies a positive drive to the clutch sprocket 46, through the sequence above described and in a direction of rotation corresponding to that in which the roll 9 is driven by tension exerted on the strip 4, by the positively driven pinch rolls, indicated at 65, Figs. 2 and 3, through which the strip passes on leaving the plating bath, these pinch rolls being positively driven by a separate motor 66, through a worm or bevel gear, indicated at 67. Sprocket 46, in turn, applies a positive drive to bushing 47a bolted thereto, and in turn to collars 48a, 49, which apply a frictional drive to sleeve 51, the slippage of which is determined by the axial pressure exerted on the collar 49 by the helical springs 56, which pressure is adjusted, as desired, by manipulation of the handwheel 54, rotation of which increases or decreases the spring pressure, by axial movement of the bushing 53. The frictional drive applied to sleeve 51, is in turn transmitted as a positive drive to the roll shaft 48, due to engagement of the radial edges of the teeth of the ratchet ring 64, secured to sleeve 51, with the driving pawls 61, 62, secured to shaft 48, through pawl holder 60, keyed to sleeve 57, which in turn is keyed to shaft 48. The clutch sprocket 46 thus applies a frictional drive to the contact roll shaft 48, the torque of which is determined by the adjustment of the handwheel 54. Adjustment of the handwheel should be so that the driving force on roll 9 will not be so great as to produce slack in the strip between contact roll assemblies. The drive thus applied to shaft 48 of roll 9 is also applied to the shaft of roll 8 by virtue of the intermeshing gears 68, 69, keyed to these shafts respectively. The amount of slippage is determined by the variation in the speed of the clutch drive over the speed of the main pinch roll drive.

Now, as explained above, the strip upon leaving the plating bath, is fed between the power-driven pinch rolls 65, Fig. 2, which apply a positive drive to the strip and thus pull the strip through the plating bath contact roll assemblages, at a surface speed determined by the speed of rotation of the power-driven pinch rolls 65. The clutch drive motor speed is adjusted so as to slightly overdrive the sprockets 46 of clutches 47. Therefore, in normal operation, the contact roll shaft 48 will be driven by the clutch drive at the speed of the strip, with a slight amount of slippage in the clutch, with handwheel 54 adjusted so as to obtain proper torque on shaft 48. If an error is made in adjusting the clutch drive motor 15 so as to make contact rolls 9 run at a surface speed less than the strip speed, the contact roll shaft

will be driven by the strip at a greater speed than the clutch sprocket 46, whereby the pawls 61, 62 will move around in the direction indicated by the inner arrow of Fig. 11 with respect to the ratchet ring 64, this being accomplished by the sloping edges of the ratchet ring teeth forcing the pawls 61, 62 inwardly against the resilient restraining action of the interposed helical spring 63.

Ideally, the positive feed applied to the strip by the exit pinch rolls 65, in turn drives the contact rolls 8, 9 at exactly the same speed as these rolls tend to be driven through the friction clutch, whereby the strip, in effect, merely "floats" on the contact rolls as it passes through the plating bath, in consequence of which the tension exerted on the strip by the exit pinch rolls remains substantially constant throughout the plating bath. This operation prevents the building up of too great a tension in the strip, such as would cause breakage, and such as would occur if the entire drive were due to pull exerted on the strip by the exit pinch rolls. Also by virtue of this operation, the strip is prevented from dragging across the faces of the contact rolls, thereby to avoid scratching and marring the surfaces of the plated strip. In certain of the claims a "first mentioned pair" of pinch rolls is referred to as "being located in advance of" a second mentioned pair of such rolls. By this is meant that the strip material passes through the "first mentioned" pair of pinch rolls before reaching the "second mentioned" pair of pinch rolls.

Considering now the electrical aspects of the apparatus, Fig. 3 indicates diagrammatically the circuits for applying current to the plating bath. A direct current generator 10 has its negative terminal connected in parallel over conductors such as 71, 72, to contact shoes 73, which bear against the contact rolls 9, the positive generator terminal being connected in parallel over other conductors, such as 14, 15, to the plating racks 10, 11. Employing the conventional direction of current flow, i. e., from the positive to the negative generator terminal, the current flow is from the positive generator terminal to the plating racks 10, 11, and to the bars of pure plating material 12, 13, such as bars of tin supported thereby, thence through the plating solution to the metal strip 4, thence along the strip to the contact rolls 9, and thence to the contact shoes 73, returning to the negative generator terminal.

As regards the electrical aspects of the apparatus as actually constructed, Figs. 2, 3, 5 and 6, show these details with respect to the plating rack assembly, while Figs. 3, 8 and 9 give the same information with respect to the contact roll assembly. The plating racks consist of a succession of U-shaped members 10, 11, dipping into the plating bath, and supported at their upper ends, on insulating blocks, such as 76, 76a, Fig. 6, composed of rubber or other suitable insulating material, these blocks being carried by the frame members 2. Also as shown in Fig. 6, bus bars 77, 78, comprising piles of copper strips, are interposed respectively between the plating racks 10, 11 and the insulating support 76. As shown in Fig. 2, these bus bars extend the length of the plating bath, and are connected to the positive generator terminal, for feeding the heavy plating current from the positive generator terminal to the plating racks.

For returning the plating current from the contact rolls 9 to the negative generator terminal,

each contact roll is provided, as stated, with a pair of metal contact shoes, composed preferably of a bronze alloy such as 90% copper and 10% tin, or other appropriate material. Each of these contact shoes consists, as shown in Fig. 9, of a single arcuately-shaped piece of metal, which is provided at its leading end with a bolt-hole 79, through which extends a bolt 80, secured to the contact roll frame 19, for pivotally supporting the shoe, which rides, by virtue of its weight, upon the contact roll as shown in Figs. 2, 8. For increasing the life of the shoe, and offsetting the effect of wear, the cross-sectional thickness of the shoe gradually increases from the leading end 79 to the trailing end 81, as shown in Fig. 9. Centrally disposed on the upper surface of the shoe is a flattened portion 82, containing tapped bores 83 for reception of terminal screws, attaching to the shoes flexible lead-in conductors 84, Fig. 8, of braided copper wire, or the like, the opposite ends of which are connected to a copper strip 85, which, in turn, extends and is connected to a bus bar 86, the latter consisting of an assemblage of copper strips, extending, as shown in Fig. 2, the length of the plating bath and supported upon the insulating block 76, Fig. 6. This bus bar is, in turn, connected to the negative generator terminal.

I claim:

1. In an apparatus for feeding continuous strip material through successive plating zones, a first and a second pair of pinch rolls between which the strip is fed, said first mentioned pair of pinch rolls being interposed between successive plating zones and being located in advance of said second mentioned pair of pinch rolls, means applying a positive drive to said second roll pair, an overrunning clutch, an adjustable friction clutch and a second source of driving power, and means for driving said first roll pair from said second source through said friction and overrunning clutches.

2. In an apparatus for feeding continuous strip material through successive plating zones, a pair of pinch rolls for feeding the strip, and means for driving said rolls including, an overrunning, frictional clutch, comprising a first driven member frictionally engaging a second driven member, and a third driven member driven through overrunning clutch means by said second member, whereby said first member applies a frictional drive to said third member, but said third member is free to overrun in the direction of said drive.

3. In an apparatus for feeding continuous strip material through successive plating zones, a pair of pinch rolls for feeding the strip, and means for driving said rolls including, an overrunning, frictional clutch comprising a first driven member frictionally engaging a second driven member, means for varying said frictional engagement, a third driven member, and pawl and ratchet means for driving said third driven member by said second member, whereby said third member is frictionally driven by said first member, but is free to overrun in the direction of said drive.

4. In an apparatus for feeding continuous strip material through successive plating zones, a pair of pinch rolls for feeding the strip, and means for driving said rolls including, an overrunning, frictional clutch comprising three concentric driven members disposed one within the other, means providing frictional engagement between the outer and intermediate members, and overrunning clutch means interposed between the in-

termediate and inner members, whereby a frictional drive is interposed between the outer and inner members, while the inner member is free to overrun in the direction of said drive.

5. In an apparatus for feeding continuous strip material through successive plating zones, a pair of shaft mounted pinch rolls for feeding the strip, and means for driving said rolls including, intermeshing gears carried by said shafts respectively, and an overrunning frictional clutch comprising three concentric members disposed one within the other, the outer member of which frictionally engages the intermediate member with means for adjusting said frictional engagement, and the intermediate member of which drives through overrunning clutch means in the inner member, whereby the outer member may frictionally drive the inner member, while the inner member is free to overrun in the direction of said drive.

6. In an apparatus for feeding continuous strip material through successive plating zones, a first and a second pair of pinch rolls, between which the strip is fed, said first mentioned pair of pinch rolls being interposed between successive plating zones and being located in advance of said second mentioned pair of pinch rolls, said roll pairs being disposed in sequence in the direction of strip feed, means for applying a continuous positive drive to said second pair of rolls, and means including overrunning, frictional slip clutch means for driving said first pair of rolls.

7. In the feeding of continuous strip material

between a first and a second pair of pinch rolls disposed in sequence respectively in the direction of said feed, the method of operation comprising applying a positive driving force to the rolls of said second pair and applying a flexible drive through an overrunning, frictional clutch to the rolls of said first pair, and so adjusting the drives on said first and second roll pairs that the rolls of the first pair normally apply force to feed the strip without slippage thereon, at a rate the same as the rate of feed of the strip by the rolls of the second pair and with the strip maintained substantially free of slack between said pairs of rolls.

8. In an apparatus for feeding continuous strip material through successive plating zones, a first and a second pair of pinch rolls disposed in sequence respectively in the direction in which the strip is fed, said first mentioned pair of pinch rolls being interposed between successive plating zones and being located in advance of said second mentioned pair of pinch rolls, means for applying a positive drive to said second roll pair, and means for driving said first roll pair including, a clutch having a first rotatable member frictionally engaging a second rotatable member, and having a third rotatable member also including an overrunning clutch means for driving said third member by said second member, means applying a positive drive to said first member, and means for driving said pinch rolls from said third member.
